Inventor,
Mary M. Gray
J. C. M. Clarke, Attorney

UNITED STATES PATENT OFFICE.

HARRY M. GRAY, OF PITTSBURG, PENNSYLVANIA, ASSIGNOR, BY DIRECT AND MESNE ASSIGNMENTS, OF ELEVEN-EIGHTIETHS TO EMIL G. BELL, TEN-EIGHTIETHS TO E. E. KRUTZ, TEN-EIGHTIETHS TO W. H. MERING, AND EIGHT-EIGHTIETHS TO J. H. MERING, OF PITTSBURG, PENNSYLVANIA, TEN-EIGHTIETHS TO GEORGE F. FELGER, OF WILKINSBURG, PENNSYLVANIA, FIFTEEN-EIGHTIETHS TO RICHARD A. OHLOFF, OF PITTSBURG, PENNSYLVANIA, AND ONE-EIGHTIETH TO ALBIN FRANKE, OF IRWIN, PENNSYLVANIA.

INGOT-MOLD.

No. 902,872.

Specification of Letters Patent.

Patented Nov. 3, 1908.

Application filed November 1, 1907. Serial No. 400,212.

To all whom it may concern:

Be it known that I, HARRY M. GRAY, a citizen of the United States, residing at Pittsburgh, in the county of Allegheny and State of Pennsylvania, have invented certain new and useful Improvements in Ingot-Molds, of which the following is a specification, reference being had therein to the accompanying drawing.

10 My invention refers to an improved ingot casting mold and it has for its object to provide a mold for casting steel or any other metal in ingot form, so as to produce an ingot having parallel walls, and to cheapen and 15 simplify the casting. The mold comprises an outer shell having inner relatively movable walls adapted to be raised and separated within the shell to release the ingot for stripping in the manner hereinafter described.

20 In the drawings:—Figure 1 is a vertical sectional view through one form of ingot mold indicated by the line I, I, of Fig. 2. Fig. 2 is a plan view of Fig. 1. Fig. 3 is a sectional view similar to Fig. 1, but showing 25 the interior walls of the mold raised and separated to release the ingot. Fig. 4 is an end view in elevation of Fig. 1. Fig. 5 is a plan view similar to Fig. 2, showing a modified arrangement of the interior relatively movable walls. Fig. 6 is a perspective detail view showing the construction of the wall used with the arrangement shown in Fig. 5. Fig. 7 is a similar perspective view showing 30 the construction of the wall used with the arrangement shown in Fig. 5.

35 2 is the outer shell of the mold of suitable form and dimensions to inclose the inner movable walls and to provide an interior cavity for the ingot. In the form shown in 40 the principal figures of the drawings the opposite inner faces 3 of shell 2 are tapered or inclined upwardly and outwardly, providing inclined seats or bearings for the inner movable sections 4, 4, the outer faces of which 45 contact with said faces 3 and are of the same degree of slope. The sides 5 of sections 4 may abut directly against each other or overlap, as indicated at 6, to provide a tight joint when the inner sections are in their lower 50 position, as in Fig. 1, for pouring.

At their upper ends sections 4 are provided with eyes 7 or any other suitable lifting mechanism by which the sections may be simultaneously raised by a crane and its connections 8 of any suitable construction, while each of said sections 4 is also provided with lifting pins 9, secured in their body portion and projecting outwardly through slots 10 in the walls of outer mold casing 2, as clearly shown, retaining pins or other devices 11 being provided if desired. By this construction, after the mold has been set upon its base, as in Fig. 1, with sections 4 depressed to the lowermost position and the inner walls thereof having approached each other, the metal is poured into the interior cavity, and when sufficiently cooled, sections 4, 4, are raised, as indicated in Fig. 3, and due to the inclined faces 3 and the corresponding outer faces of sections 5 abutting thereon, sections 4 are caused to separate outwardly away from contact with the ingot A, leaving it resting upon the base, and upon continuous raising by the crane, pins 9 come into contact with the upper ends of slots 10, whereupon the outer mold 2 and the entire apparatus may be bodily lifted away from the ingot.

In Fig. 5 I have shown a construction wherein the inner sections 4' are L-shaped and provided on both sides with tapering 80 faces adapted to contact with correspondingly tapered faces around the inner four walls of the outer mold 2', said sections 4' being also provided with lifting eyes 7', preferably located at their corners to equalize the weight. 85 By this construction it will be seen that upon lifting sections 4' they will recede away from the ingot at all sides thereof, each section traveling outwardly toward the direction of its corner, each section separating in corresponding opposite directions. With either construction the release of the ingot and the avoidance of a frictional contact between it and the inner mold faces, results in an immediate stripping without the necessity of the 90 employment of any additional force, so that the mold is easily and readily withdrawn, the ingot retaining its position by the mere force of gravity.

If it is desired to reverse the ingot mold, 100

the pins 9 may be extended upwardly sufficiently far to serve as trunnion bars, and mounted in bifurcated extremities 12 of a suitable support, as indicated by dotted lines 5 of Fig. 4. By this construction the entire mold may be raised or lowered and manipulated and also reversed if desired, for the purpose of solidifying the metal of the ingot after casting.

10 It will be understood that the mold may be made in any desired form, size, or cross section, and it will be found to give the desired results in practice, avoiding the objectionable sticking of the ingot.

15 Changes or variations may be made by the skilled mechanic in various features without departing from the invention as covered by the following claims.

What I claim is:—

20 1. An ingot mold having interiorly tapered walls and inner sections having tapered faces seated thereon and adapted to be moved and to recede outwardly, substantially as set forth.

25 2. An ingot mold consisting of an outer shell having inner longitudinally tapering faces, and a plurality of separable assembled lining sections having corresponding tapered bearing faces.

30 3. An ingot mold consisting of an outer shell having inner longitudinally oppositely tapering faces, and a plurality of separable assembled lining sections having corresponding oppositely tapered bearing faces.

4. An ingot mold consisting of an outer shell having inner longitudinally tapering faces, a plurality of inner sections set directly thereon having corresponding tapered faces, and means for lifting said sections, substantially as set forth. 35

5. An ingot mold consisting of an outer shell having inner longitudinally tapering faces and provided with lining sections having abutments adapted to engage and lift the outer shell after preliminary raising, and means for lifting said sections, substantially 40 as set forth. 45

6. In an ingot mold, the combination of an outer shell having inner longitudinally tapered faces and oppositely arranged slots, inner molding sections having correspondingly tapered bearing faces and provided with studs extending outwardly through said slots, and means for lifting the sections, substantially 50 as set forth. 55

7. In an ingot mold, the combination of an outer shell having interior diverging bearing faces, and interior lining sections having corresponding faces and arranged for movement longitudinally of the mold cavity and for separation from each other. 60

In testimony whereof I affix my signature in presence of two witnesses.

HARRY M. GRAY.
